UNITED STATES PATENT OFFICE.

JAMES E. HEWES, OF PLATTSBURG, NEW YORK, ASSIGNOR OF ONE-HALF TO CHARLES H. BOONE, OF BALTIMORE, MARYLAND.

ELECTRIC FURNACE.

No. 820,574.

Specification of Letters Patent.

Patented May 15, 1906.

Application filed July 18, 1905. Serial No. 270,184.

To all whom it may concern:

Be it known that I, JAMES E. HEWES, of Plattsburg, county of Clinton, and State of New York, have invented an Improvement in Electric Furnaces, of which the following is a specification.

My invention has reference to electric furnaces; and it consists of certain improvements, which are fully set forth in the following specification and shown in the accompanying drawings, which form a part thereof.

The object of my invention is to provide a suitable construction of furnace for employing electricity in the production of carbid of calcium and other highly - refractory substances which shall have capacity for continuous operation and without danger of short-circuiting or production of inferior carbid and waste of smelting material.

20 My improved furnace embodies a trough-shaped hearth to contain the lime and carbon or other material to be smelted combined with two electrodes arranged at an angle to each other and creating an arc within the materials supported in the trough-shaped hearth.

25 My invention further consists in providing means for slowly feeding or moving the hearth past the electrodes, so as to convey the carbid of calcium under one of the electrodes beyond the arc or zone of fusion immediately after it is made and whereby the process of making the carbid of calcium is a continuous one.

30 My invention also comprehends many details of construction, which, together with the features above specified, will be better understood by reference to the drawings, in which—

35 Figure 1 is a longitudinal sectional elevation of an electric furnace embodying my invention. Fig. 2 is a plan view of same, and Fig. 3 is a cross-section of the same looking toward the feeding end.

40 A is the main frame of the furnace and is provided with two endless carriers or chains B, adapted to be intermittently moved over guides B'. They are driven by sprocket-wheels C and transverse shafts C', geared at I by worm and worm-wheels with a driving-shaft I'. This driving-shaft I' receives motion from a motive-power device known as a "Replogle governor" or in any other suitable manner.

D represents a series of trough-shaped hearth-plates, which fit end to end and have flanges at the top which rest upon the traveling chains or carriers B. As the chains are moved along additional hearth-plates D are added from time to time to the feeding end, and corresponding plates with the product are removed from the distant end of the series. This forms a traveling hearth.

J is a shield fitting down into the trough-like hearth-plates, but permitting them to travel beneath it, and said shield supports a tube G, having yoke G'.

F is a tube sliding in the tube G and in which the carbon electrode E is carried. This electrode is horizontal and adjustable in the direction of the travel of the plates D by means of a hand-controlled adjusting-screw H or its equivalent acting on the yoke G' and tube F. K is the other or vertical electrode and is fed through a guide-insulator L and is held at substantially right angles to the horizontal electrode E, so that the electric arc extends between the two electrodes and there is a continuous space below the vertical electrode in alinement with the horizontal electrode, through which space the fused carbid of calcium may be conveyed away from the horizontal electrode by the travel of the trough-shaped hearth-plates D.

Surrounding the electrodes and above them and the hearth-plates D is a hood M, through which opens a chute or hopper N for supplying lime and carbon into the trough or hearth about the electrodes, so that a continuous supply of the material to be smelted may be provided to compensate for that conveyed forward by the traveling plates D. There is also a chimney or flue N' opening from said hood M, preferably beyond the vertical electrode, to convey away the gases and fumes generated.

95 Current is supplied to the electrodes by suitable circuits and may be controlled or regulated in any manner desired. The vertical electrode is suspended by the cable O, which terminates in a screw-shaft P, that may be screwed into or out of a fixed nut P' for the purpose of raising or lowering the electrode K. Any other manner of adjusting the electrode may be employed, if so desired.

100 The governor S is controlled to rotate the

shaft I' in one direction or the other, according to whether the contact T on the screw-shaft P is made to close the circuit R R' or the circuit R R², which lead from a battery S' to the governor S; but as the particular details of the governor are all old and no claim is made to any of its parts, no further description of it will be necessary. While some automatic feeding device for the conveyor-chains is desirable, the shaft I' may be rotated by hand, if preferred.

One of the excellent advantages of my improvement consists in the capacity to control the thickness of the finished product, this capacity being due to the fact that I employ the electrodes at right angles, and consequently can vary the vertical extent of the arc employed to fuse the burden. Moreover, by imparting to the trough-shaped hearth a uniform movement—for example, about twelve inches per hour—the carbid of calcium produced is gradually and uniformly carried away from the horizontal electrode E and out of the zone of the arc, so that there is no tendency whatever to short-circuit the furnace. Furthermore, by having capacity to vary the distance between the electrodes and also to control the travel of the arc I am enabled to operate with either a constant current or a variable current and a constant or variable voltage, as desired. In practice I prefer that the vertical electrode shall be above and that the current shall pass from the vertical electrode to the horizontal one.

In starting the furnace the vertical electrode is lowered to the horizontal electrode, so as to close the circuit between them. The horizontal electrode is then drawn slowly backward by means of the screw H, so as to approximate eight inches from the vertical electrode, and then the vertical electrode is slowly raised until the desired height is obtained to secure the proper thickness of the ingot being formed in the materials to be smelted or burden which is deposited in the furnace through the hopper. Ordinarily this burden is composed of sixty per cent lime and forty per cent carbon ground together and thoroughly mixed. If the furnace is used for any other purpose than the manufacture of carbid of calcium, the mixture would of course be varied.

While I have shown the preferred construction of my invention, I do not confine myself to the details, as these may be varied in many ways without departing from the spirit of the invention.

Having now described my invention, what I claim as new, and desire to secure by Letters Patent, is—

1. In an electric furnace, the combination of a trough-like hearth for the materials to be smelted having side flanges, two electrodes arranged at an angle to each other one of

said electrodes being in alignment with the length of the trough-like hearth, two side guides B' on each side of the hearth, endless traveling chains or conveyers B B traveling over and resting above said guides and directly supporting the flanges of the hearth. 65

2. In an electric furnace the combination of a trough-like hearth for the materials to be smelted, two electrodes arranged at an angle to each other one of said electrodes being in alignment with the length of the trough-like 70 hearth, and means for causing a relative movement between the electrodes and the hearth whereby the smelted materials are conveyed away from the electrodes.

3. In an electric furnace the combination of a trough-like hearth for the materials to be smelted, two electrodes arranged at an angle to each other one of said electrodes being in alignment with the length of the trough-like 80 hearth, and means for feeding the hearth longitudinally and relatively to the electrodes. 85

4. In an electric furnace the combination of a longitudinally-traveling trough-shaped hearth, a horizontal electrode arranged within the hearth, a vertical electrode at a higher elevation than the horizontal electrode so as to leave a space below the vertical electrode in alignment with the horizontal electrode; a hood surrounding the electrodes and the hearth adjacent to them and a depending 90 shield J fitting down into the trough-shaped hearth and around the horizontal electrode to close the hearth and yet permit it to be moved forward.

5. In an electric furnace the combination of a hearth, a horizontal electrode arranged at a higher elevation than the horizontal electrode so as to leave a space below the vertical electrode in alignment with the horizontal electrode and means for feeding the hearth 100 longitudinally under the electrodes. 105

6. In an electric furnace, the combination of a hearth, a horizontal electrode arranged above the hearth, a vertical electrode at a higher elevation than the horizontal electrode 110 so as to leave a space below the vertical electrode in alignment with the horizontal electrode, means for feeding the hearth longitudinally under the electrodes, and stationary means for feeding the materials to be smelted 115 to the electrodes.

7. In an electric furnace the combination of two electrodes with a sectional hearth formed of a series of trough-like plates detachably abutting and forming a rectilinear trough, and a common carrier for holding the plates in alignment and conveying them past the electrodes, consisting of two traveling chains and guides therefor whereby they form traveling rectilinear supports. 120

8. In an electric furnace the combination of two electrodes with a sectional hearth formed of a series of trough-like plates de-

tachably abutting and forming a rectilinear trough, a common carrier for holding the plates in alinement and conveying them past the electrodes, consisting of two traveling chains and guides therefor whereby they form traveling rectilinear supports, and means for operating the common carrier or conveyer.

In testimony of which invention I hereunto set my hand.

JAMES E. HEWES.
